[57] CLAIM

The ornamental design for a rotary tool, as shown and described.

DESCRIPTION

The handpiece of electric appliance of the present design relates to an electric tool for precisely cutting, polishing, and boring, and is used for jewel making, metal-carving, metal mold finishing, a medical purpose, a dental purpose, or the like.

FIG. 1 is a front view of a rotary tool showing my new design;

FIG. 2 is a rear view thereof;

FIG. 3 is a right side view thereof;

FIG. 4 is a left side view thereof;

FIG. 5 is a top plan view thereof;

FIG. 6 is a bottom plan view thereof; and,

FIG. 7 is a perspective view thereof.
